UNITED STATES PATENT OFFICE.

SIDNEY E. CORNISH, OF BERKELEY, CALIFORNIA, ASSIGNOR OF ONE-HALF TO H. H. PLUMMER, OF SAN FRANCISCO, CALIFORNIA.

DRYING-KILN.

1,376,319.

Specification of Letters Patent. Patented Apr. 26, 1921.

Application filed January 20, 1920. Serial No. 352,743.

To all whom it may concern:

Be it known that I, SIDNEY E. CORNISH, a citizen of the United States, and a resident of Berkeley, in the county of Alameda and 5 State of California, have invented a new and Improved Drying-Kiln, of which the following is a full, clear, and exact description.

This invention relates to improvements 10 in drying kilns, an object of the invention being to provide a kiln having a transverse draft of heated air to dry the material movable longitudinally through the kiln.

A further object is to provide a drying 15 kiln having means for moving material longitudinally therein and means for compelling a continuous circulation of air from the dry end of the kiln to the charging end of the kiln and in such movement compel 20 the air to pass crosswise or transversely through the kiln any desired number of times.

A further object is to provide a kiln of 25 improved construction having heating means therein with draft creating devices compelling the hot air to travel in a continuous path from the dry end to the charging end and in such path of movement pass transversely and at an angle through the kiln the 30 desired number of times.

With these and other objects in view the invention consists in certain novel features of construction, and combinations and arrangements of parts, as will be more fully 35 hereinafter described and pointed out in the claims.

In the accompanying drawings—

Figure 1 is a broken view in side elevation illustrating my improvements;

40 Fig. 2 is a broken plan view;

Fig. 3 is an enlarged view in transverse section on the line 3—3 of Fig. 2;

Fig. 4 is a fragmentary perspective view 45 illustrating a preferred manner of piling veneer for drying in the kiln; and

Fig. 5 is an exaggerated view in section of a fragment of the kiln wall.

A represents my improved drying kiln 50 which is preferably made up in sections so that it can be formed of any desired length. The walls of the kiln are rendered non-heat conducting in any approved manner, a simple illustration of this, and which I deem a desirable construction, is shown in Fig. 5, 55 in which corrugated asbestos lining strips

1 are located between thicknesses 2 and serve to form dead air spaces in the non-heat conducting walls. The invention, of course, is not limited to the particular manner of constructing the walls as this might be done in 60 various ways.

A conveyer is provided in the kiln and comprises a pair of endless chains 3 supported on suitable framework 4 and driven by sprocket wheels 5 at one end of the kiln. 65 The kiln is heated preferably by steam pipes 6 arranged between and at the sides of the chains 3 and may be of any desired length to give the necessary results. A charging door 7 is provided at one end of the kiln 70 and a discharging door 8 at the other end of the kiln so that these doors may be closed during the drying operation.

Fans 9 are provided at one side of the kiln spaced apart the desired distance and arranged in staggered relation to air outlets 9^a at the other side of the kiln and are connected with said air outlets by means of flues 10 extending transversely above the kiln and diagonally, as clearly indicated in Fig. 2. This arrangement of fans and flues compels the air from the dry end of the kiln to pass to the charging end of the kiln in a circuitous path, as indicated by the arrows in Fig. 2. In other words, the air is drawn 85 or blown transversely of the kiln in a continuous path and caused to move across through the kiln the desired number of times in accordance with the number of fans and flues and finally finds an exit through 90 a ventilator head 11 adjacent the charging end of the kiln. While, of course, my invention is not limited to the particular means for operating the conveyer and driving the fans, I have illustrated a power 95 transmission means which can be conveniently employed.

A motor 12 drives a belt 13 which turns a pulley 14 on a countershaft 15. This countershaft 15 has two pulleys 16 and 17 thereon, the former connected by a belt 18 with a pulley 19 on a shaft 20. The shaft 20 is provided with a gear train 21 which reduces the speed of sprocket wheels 22, the latter connected by chains 23 with sprocket 105 wheels 24 on the shafts 25 carrying the sprocket wheels 5, above referred to. The pulley 17 is connected by a belt 26 with a pulley 27 on an intermediate fan shaft 28. This shaft 28 is provided with two other 110

pulleys 29 and 30, the former connected by a belt 31 with a pulley 32 on another fan shaft 28. The pulley 30 is connected by a belt 33 with a pulley 34 on the other fan shaft 28.

5 While, of course, my improved kiln may be utilized for drying fruit or for any other purpose for which it is adapted, it is primarily adapted for drying veneer and I have illustrated in Fig. 4 a pile of veneer 35 spaced 10 apart by blocks or strips 36 and adapted to be positioned on the conveyer chains 3 and moved longitudinally of the kiln so that the transverse drafts of air will have a free passage through the pile of veneer and freely 15 dry the same.

The veneer is preferably positioned with its grain running transversely of the kiln and in a substantial line with the draft. By constructing a kiln, as above described, the 20 air from the dry end of the kiln is caused to move to the charging end of the kiln in a circuitous transverse path to take up the moisture of the material being dried, and while, of course, the temperature of the air 25 is not materially decreased, it becomes more and more charged with moisture as it reaches the ventilator head so that the incoming green material is not subjected to the intense dry air which it receives as it reaches 30 the dry end of the kiln and hence, the drying operation is carried out slowly and in the proper stages to give the best results.

The arrangement of fans is such that they 35 cause a circulation nearly equal on all of the material or stock as the kiln is relatively narrow and as the blast is practically the same at both sides of the kiln. Hence, the stock will be dried uniformly as it passes through the kiln.

40 It is, of course, to be understood that the temperature of the kiln can be controlled in accordance with the work to be done and the draft of air regulated to precisely suit conditions. The kiln may be operated as a continuous drier through which the stock or material is passed or the stock may be allowed to remain in the kiln for any desired length of time.

Various slight changes may be made in the general form and arrangement of parts 50 described without departing from the invention, and hence I do not limit myself to the precise details set forth but consider myself at liberty to make such changes and alterations as fairly fall within the spirit 55 and scope of the appended claims.

I claim:

1. A kiln, fans at one side of the kiln, and flues connecting the fans with the other side of the kiln, whereby a continuous circuitous 60 circulation of air is provided transversely through the kiln.

2. A kiln, a plurality of fans located at one side of the kiln, said kiln having air outlets at its other side, diagonally positioned flues 65 connecting the fans on one side of the kiln with the outlets on the other side of the kiln, and means for operating the fans to force the air transversely of the kiln and in an inclined direction toward the charging end of 70 the kiln.

3. A kiln, comprising a longitudinal series of sections, the walls of said sections composed of non-heat conducting material, a conveyer extending longitudinally of the 75 kiln, steam pipes in the kiln, fans adapted to blow transversely of the kiln, and means for transmitting power to said fans and to said conveyer.

4. A kiln, fans at one side of the kiln, and 80 flues connecting the fans with the other sides of the kiln whereby a continuous circuitous circulation of air is provided transversely through the kiln, and said kiln being formed of a series of sections, the walls of said sections composed of non-heat-conducting material.

5. A kiln, fans at one side of the kiln, and flues connecting the fans with the other sides of the kiln whereby a continuous circuitous 90 circulation of air is provided transversely through the kiln, a conveyer in said kiln, and means for simultaneously operating the fans and the conveyer.

SIDNEY E. CORNISH.
